PIVOTED LINK CHAIN

Leon E. Simmons, Claremont, N. H., assignor to
 Sullivan Machinery Company, a corporation of
 Massachusetts

Application November 26, 1942, Serial No. 466,995

8 Claims.

(Cl. 74—254)

This invention relates to pivoted link chains, and more particularly to improvements in cutter chains especially designed for use in the mining of coal.

An object of the present invention is to provide an improved pivoted link chain. Another object is to provide an improved chain having novel pivotal connections between the associated chain elements. A further object is to provide an improved hinge pin construction for a cutter chain. Yet another object is to provide an improved lock for holding the hinge pin bushings stationary with respect to the chain block bores. A still further object is to provide an improved means for holding the hinge pin against axial displacement. With these and other objects in view, this invention relates to certain novel features of construction, operation, and arrangement of parts, an example of which is given in the specification and illustrated in the accompanying drawing, wherein:

Fig. 1 is a side elevational view of a section of the cutter chain constructed in accordance with an illustrative embodiment of the invention.

Fig. 2 is a detail cross sectional view taken substantially on line 2—2 of Fig. 1.

Fig. 3 is a view in longitudinal section taken substantially on line 3—3 of Fig. 1.

Fig. 4 is a vertical sectional view taken substantially on line 4—4 of Fig. 3, showing the bushing lock.

Fig. 5 is a perspective view of one of the hinge pin parts.

In this illustrative embodiment of the invention, there is shown a cutter chain comprising a series of chain blocks 1 pivotally connected together by a series of strap links 2. The cutter chain is adapted to travel about the margin of a conventional cutter bar, and the strap links have lateral gibs 3 adapted to engage the cutter bar guideways in a well known manner. The chain blocks have lateral lugs 4 having sockets for the reception of usual cutter bits 5, the latter being held in position by conventional set screws 6.

The chain blocks have transverse bores 7, and the strap links have bores 8 in registry with the block bores, and the strap link bores have end enlargements or recesses 9. Arranged in the bores of the blocks are pivot elements or bushings 10, and extending through these bushings and disposed in the strap link bores are hinge pins 11 of a novel design. These pins serve pivotally to connect the links to the block and to hold the links together as will later be explained. The chain blocks have longitudinal bores 12 extending

between the transverse bores 7, and arranged in the bores 12 are lock pins 13 having their ends projecting within notches 14 in the bushings, for locking the latter against rotation in the block bores. By holding the bushings against rotation relative to the blocks, wear is concentrated on the bushings which are much cheaper to replace than the chain blocks.

The hinge pins each comprise three separable parts including a pair of cooperating, nearly semi-cylindrical, pin elements 15 having flangelike end enlargements or projections 16 adapted to be received in the end enlargements 9 of the strap link bores and so shaped as to be withdrawable through the bores of the bushings when the spacer elements next to be described are removed. Interposed between the outer pin parts 15 is a spacer element or intermediate pin part 17 in the form of a rectangular plate which serves to hold the outer pin parts 15 in proper spaced relation with the end enlargements 16 seated in the end enlargements of the strap link bores. When the pin enlargements are positioned in the bore enlargements the strap links are held together by the pins. This rectangular spacer plate 17 is slotted at 18, and the portions 19 of the spacer plate are adapted to be bent laterally into slots 20 in the outer sides of the strap links in the manner shown in Fig. 3, to lock the hinge pin parts against axial displacement. The spacer plate is preferably slotted at both sides so that it can be reversed when desired.

When it is desired to remove the hinge pins, the bent portions 19 of the spacer plates may be straightened to release the same from the notches 20 in the strap links, thereby to free the spacer plates for endwise removal from between the outer hinge pin parts 15. Upon removal of the intermediate spacer plates the outer pin parts 15 may be easily removed from the bushing and strap link bores in an obvious manner. When the strap links are detached from the chain blocks the bushings 10 may be easily driven out of the chain block bores without disturbing the locking pins 13, the bushings being movable axially to release their notches 14 from engagement with the ends of the locking pin. It is accordingly evident that a novel hinge pin structure is provided which may be easily put together or taken apart and which is of relatively inexpensive design, enabling ready and inexpensive replacement of worn or broken parts. By constructing the hinge pin parts in the manner disclosed, the hinge pin and bushings are positively locked in assembled relation. The pin lock for the bushings prevents the

rotation of the bushings, thereby eliminating wear of the block bores. The bushings likewise may be readily and inexpensively replaced when worn. Other uses and advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a pivoted link chain, a chain element having transverse bores, bushings fitted in said bores, and a common locking element extending between said bushings for holding the latter against rotation in said bores.

2. In a pivoted link chain, a chain element having transverse bores, bushings fitted in said bores, a longitudinal bore extending between said transverse bores, and a pin arranged in said longitudinal bore and engaging said bushings for locking the latter against rotation in said transverse bores.

3. In a pivoted link chain, a chain element having transverse bores, bushings fitted in said bores, a longitudinal bore extending between said transverse bores, and a pin arranged in said longitudinal bore and engaging said bushings for locking the latter against rotation in said transverse bores, said bushings being notched to receive the ends of said pin.

4. In a pivoted link chain, pivotally connected chain elements, one of said elements having transverse bores, pivot elements received in said bores respectively, and a holding member extending longitudinally of said transversely bored element between the bores thereof and engaging said pivot elements for holding the latter against rotation in said transverse bores, said holding member being common to both pivot elements.

5. As a part of a pivot element for a pivoted link chain, a flat rectangular spacer element adapted to space associated elements and having its ends slotted longitudinally to provide relatively flexible, laterally bendable locking portions at the ends of said spacer element and at each side thereof, the locking portion at one side of

each end of said spacer element being bendable laterally into locking relation with an associated chain link, and said bent locking portions when straightened permitting endwise release of said spacer element in either direction, said spacer element being reversible with respect to its associated elements and positionable in a reversed spacing position to bring the locking portions at the other side thereof into effect.

10 6. As a part of a pivot element for a pivoted link chain, a flat rectangular spacer element adapted to space associated elements and having relatively flexible, laterally bendable locking portions at its ends and at each side thereof, the locking portion at one side of each end of said spacer element being bendable laterally into locking relation with an associated chain link, and said bent locking portions when straightened permitting endwise release of said spacer element in either direction, said spacer element being reversible with respect to its associated elements and disposable in a reversed spacing position to bring the locking portions at the other side thereof into effect.

25 7. In a chain, pivotally connected chain elements, one of which has transverse bores, pivot elements received in said bores respectively and each having a notch opening through an end thereof, and a holding member extending longitudinally of said transversely bored element between the bores thereof and having its ends received in said notches for holding said pivot elements against rotation in said transverse bores, said holding member being common to both pivot elements, and said notches permitting axial release of said pivot elements from said transverse bores while said holding member remains stationary with respect to its associated chain element.

30 8. As a part of a pivot element for a pivoted link chain, a flat rectangular spacer element adapted to space associated elements and having its ends slotted longitudinally near one side to provide relatively flexible, laterally bendable locking portions, said locking portions being bendable laterally into locking relation with an associated chain link, and said bent locking portions when straightened permitting endwise release of said spacer element with respect to its associated elements in either direction.
